SPINNING FRAME DRIVE

Paul B. Reeves, Columbus, Ind., assignor to Reeves Pulley Company, Columbus, Ind., a corporation of Indiana

Application September 19, 1932, Serial No. 633,826

19 Claims. (Cl. 118—32)

The present application relates to means for driving spinning frames, and more particularly to driving means of such character that the speed of operation of the spinning frames controlled thereby shall be automatically varied in accordance with the requirements of the driven machines.

A primary object of the invention is to provide driving mechanism for a spinning frame of such character that, as thread is wound onto the bobbins of the spinning frame, the speed of operation of the machine will be automatically varied, whereby the time required to fill a set of bobbins shall be reduced; and whereby the number of breaks occurring as the bobbins are filled will likewise be reduced. A further object of the invention is to provide mechanism of the type above described which shall be entirely mechanical in character, and which shall not depend upon variation in speed of the driving motor. Further objects of the invention will appear as the description proceeds.

To the accomplishment of the above and related objects, my invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a perspective view of an end of a spinning frame of well known type having associated therewith driving mechanism constructed in accordance with the present invention;

Fig. 2 is a fragmental perspective, taken substantially at right angles to the right of Fig. 1, and showing only the driving mechanism;

Fig. 3 is a rear view of the mechanism controlling the speed of operation of the machine;

Fig. 4 is a fragmental view of a detail, taken upon an enlarged scale, parts being broken away for clarity of illustration;

Fig. 5 is a side elevation of a modified form of driving mechanism;

Fig. 6 is an end elevation taken at right angles to the plane of Fig. 5; and

Fig. 7 is a plan view of the structure illustrated in Figs. 5 and 6.

Referring more particularly to the drawings, and specifically to Figs. 1 to 4 inclusive, it will be seen that I have illustrated a spinning frame indicated generally at 10. In the drawings, the frame is shown operating to effect a warp wind of yarn on the bobbins, and the drive mechanism illustrated is so constructed and arranged as to

control the machine properly for performing warp winding operations, but it will be understood that the broad principles illustrated and described herein may be applied, through a slight adaptation of the particular construction illustrated, to perform a filling wind operation, or a combination filling wind. The spinning frame 10 comprises a frame or skeleton 11 upon which are suitably mounted a plurality of bobbin spindles 12 with which is associated a ring rail 13 carrying a plurality of travelers 14, one traveler being associated with each bobbin spindle. Yarn is led to each of the bobbin spindles, such yarn being indicated at 15.

In accordance with well understood principles of operation, the ring rail 13 is reciprocated, during operation of the machine, in order to distribute the yarn properly over the surface of the bobbins, the reciprocation of the ring rail being effected by a rod or piston 16 which is actuated by an arm 17 carried by an oscillated shaft 18. The whole machine is driven through a main shaft 19, it being understood that said shaft 19 is so associated with the other elements of the mechanism as to rotate the bobbin spindles 12 and oscillate the shaft 18 at a frequency suitable to effect the desired distribution of yarn over the surfaces of the bobbins. In the machine illustrated, of course, the ring rail 13 is reciprocated at a frequency such as to lay the yarn or thread 15 on the bobbins in a series of layers, each extending over substantially the whole vertical length of the bobbins, this method of winding being known as warp winding.

Associated with the spinning frame 10 is the driving unit comprising a base 20 formed to provide a slideway 21 in which is slidably mounted a plate 22 carrying a motor 23. Said motor 23 is provided with a spindle or shaft 24 which is positioned in parallelism with the shaft 19. Said shaft 24 carries a pulley 25, which is preferably a V-pulley, and the shaft 19 carries an expandable pulley which consists of the two oppositely facing coned discs 26 and 27. The disc 26 is rigidly mounted on the shaft 19, and the disc 27 is mounted thereon for sliding movement axially of said shaft 19, said disc 27 being urged toward the disc 26 by a spring 28 sleeved over the shaft 19 and abutting at one end against the disc 27 and at its opposite end against a collar 29. In the form of mechanism illustrated in Figs. 1 to 4 inclusive, the outer end of shaft 19 is carried in a bearing 30 which is supported on an arm or bracket 31 secured to the frame 11 of the spinning frame 10. An edge-active belt 32 forms

a driving connection between the pulley 25 and the discs 26 and 27.

Suitably journalled in the base 20 is a threaded shaft 33, said shaft having threaded cooperation with a hub 34 formed on or suitably secured to the plate 22. Said shaft 33 may carry at its upper end a hand wheel 35 whereby said shaft may be rotated; and it will be obvious that, as said shaft is rotated, the cooperation of the threads of the shaft 33 with the threads of the hub 34 will cause reciprocation of the plate 22 in the slideway 21, the shaft 33 being journalled in the base 20 against axial movement.

As the plate 22 is moved, it carries with it the motor 23 and its shaft 24, thereby varying the distance between the shafts 24 and 19. Obviously, as the distance between said shafts is increased, the belt 32 will force the disc 27 to the left, as viewed in Fig. 2, against the tendency of spring 28; thereby reducing the effective diameter of the expansible pulley 26-27 to increase the speed at which the shaft 19 is driven.

Upon the shaft 18 there is rigidly mounted an arm 36 provided with a plurality of apertures 37 or the like whereby there may be secured to said arm 36 at points differently spaced from the axis of the shaft 18, one end of a link 38. The opposite end of said link 38 is adjustably secured to an arm 39 which forms a part of ratchet mechanism 40, said ratchet mechanism including a shaft 41, and being of such character that said shaft is rotated upon movement of the arm 39 in one direction, and is unaffected by movement of the arm 39 in the opposite direction.

The shaft 41 carries a bevel gear 42 which meshes with a pinion 43 mounted on the shaft 33, said pinion 43 being held against movement axially of the shaft 33 but being rotatable with respect to said shaft.

Formed integrally with, or suitably secured to, the pinion 43 is a hub 44 provided with teeth 45. Splined on the shaft 33 is a clutch member 46 having teeth 47 adapted for engagement with the teeth 45 of the hub 44. Said clutch member 46 is provided with a flange 48 against which abuts one end of a spring 49 sleeved over the shaft 33, the opposite end of said spring 49 bearing against a ring 50 supported upon a ball bearing 51. The spring 49 tends always to urge the teeth 47 of the clutch member 46 into engagement with the teeth 45 of the hub 44, thereby connecting the pinion 43 to drive the shaft 33.

Pivoted on the base 20 at 52 is a lever 53, one arm 54 of which is formed with a yoke portion 55 which straddles the shaft 33 and the hub 44 and which bears against the upper surface of the flange 48 of the clutch member 46.

The plate 22 carries a threaded hub 56 in which is adjustably mounted a threaded stop screw 57 adapted, when the plate 22 is moved downwardly in the slideway 21, to engage the arm 54 of the lever 53. There may be provided a stop element 58 to limit the downward movement of the arm 54 of said lever 53, and to limit likewise the downward movement of the plate 22.

The opposite arm 59 of the lever 53 is suitably apertured to receive one end of a link 60, said link carrying an adjustable stop 61 which cooperates with the under surface of said lever arm 59. The upper end 62 of the link 60 is suitably secured to a finger 63 carried by a rocker journalled at 64 in the base 20. Said rocker is provided with a handle 65 whereby said rocker may

be shifted to lift the link 60, thereby lifting the arm 59 of the lever 53.

The plate 22 carries a hub 66 with which is adjustably associated a pin 67 so positioned that, when the plate 22 is moved upwardly in the slideway 21, said pin 67 will engage an arm 68 carried by the rocker to cause movement of the rocker to depress the link 60.

It is known that, as the thread or yarn builds up on the bobbins, the tension on the yarn which exists between the travelers and the bobbins is reduced. It follows that speed of operation can be increased without causing an increase in the amount of breakage, as the yarn is built up on the bobbins.

If the machine is to be driven at a constant main shaft speed, obviously that speed must be slow enough throughout the winding of the bobbins so that breakage will not be unduly high at the beginning of the run when the tension is at a maximum. It follows that, during a large part of the run of the machine, the machine is operating at an inefficiently slow speed—that is, at a speed which is slower than necessary to prevent undue breakage. In actual practice, in the past, a compromise has been effected, and the machines have ordinarily been driven at a speed which is higher than optimum for starting the wind, but which is lower than is feasible for the latter portions of the wind. As a result, the operation as a whole has taken a longer time than necessary, and there has been an unduly large amount of breakage during the early stages of the wind.

Furthermore, if a spinning frame is operated at constant speed, whereby the tension between the travelers and the bobbins varies during the wind, obviously the size and strength of the thread being wound varies during the wind.

For both of these reasons, then, it is desirable to maintain an optimum tension between the travelers and the bobbins at all times, and that can be done only by gradually increasing the speed of rotation of the bobbins as the bobbins are filled. When such a procedure is followed, the machines may be started at a speed lower than that which is used in practice in the case of constant speed machines, whereby breakage is materially reduced; and that speed of operation may be increased as the wind proceeds, whereby the period of time required to complete a run is materially reduced.

Needless to say, the variation in operating speed of the machine should be automatically and mechanically controlled in order to obtain best results.

All of the above outlined desirable functions have been accomplished by the structure herein described, the operation of such structure being as follows:—The spinning frame is threaded, and the plate 22 is set in a position such that the speed ratio between the motor shaft 24 and the main shaft 19 will be the proper one to drive the spindles at optimum speed for starting. The motor 23 is then energized and the shaft 19 is driven from the motor shaft 24 through the V-belt 32.

As the shaft 18 oscillates, the arm 39 is oscillated, and such oscillation of the arm 39, through the ratchet mechanism 40, causes step-by-step rotation of the shaft 41 in a direction to drive the shaft 33 to move the plate 22 downwardly in the slideway 21. Desirably, a brake 69 is associated with the shaft 41 or with the gear 42 to prevent the shaft 41 from overrunning or from

returning. As the plate 22 moves downwardly, carrying with it the motor 23 and its shaft 24 and pulley 25, the distance between the centers of the shafts 24 and 19 is increased. The belt 32 being of constant length is thus forced more deeply into the notch formed between the discs 26 and 27. Such movement of the belt 32 causes, by coaction with the coned face of the disc 27, movement of the disc 27 to the left, as viewed 10 in Fig. 2, against the tendency of the spring 28. Since the belt 32 has been moved more deeply into the notch between the discs 26 and 27, the effective diameter of the pulley 26-27 is decreased, thereby increasing the speed of rotation of said pulley and the shaft 19.

As the yarn is built up on the bobbins, the shaft 18 continues to oscillate and, through the above described mechanism, to rotate the shaft 33, whereby the plate 22 is continuously moved 20 downwardly. Eventually, and just before the optimum high speed of the shaft 19 is reached, the screw 57 comes into contact with the arm 54 of the lever 53. As the plate 22 continues to move downwardly to cause the shaft 19 to approach and reach optimum speed, the lever 53 is moved in a counterclockwise direction, as viewed in Fig. 3, and said lever, because of its engagement with the flange 48, carries with it the clutch member 48. At the moment when 25 optimum high speed of the shaft 19 is reached, the continued movement of the lever 53 moves the teeth 47 out of engagement with the teeth 45, thereby releasing the pinion 43 from driving engagement with the shaft 33.

Operation of the frame is then continued at this optimum high speed until the bobbins are filled, when the operator will stop the machine by deenergizing the motor 23.

The operator then removes the filled bobbins 30 from the spinning frame and replaces them with empty bobbins. He then rotates the handle 65 in a counter clockwise direction, as viewed in Fig. 1, to lift the link 60. As said link 60 is lifted, the abutment 61 comes into engagement 35 with the lower surface of the arm 59 of lever 53 and, it being understood that the finger 63 is so positioned as to cause the link 60 to operate as a toggle, it will be seen that the lever 53 will be held by said link and finger in a position 40 such as to prevent engagement of the teeth 47 with the teeth 45. The operator now rotates the hand wheel 35 to elevate the plate 22 to starting position. As the plate 22 is moved upwardly, and the shaft 24 approaches the shaft 19, the spring 28 will cause the disc 27 to move back toward the disc 26 to starting position, the belt 32 being thereby moved outwardly in the 45 notch between the discs 26 and 27. As the plate 22 approaches starting position, the pin 67 will engage the arm 68 to return the rocker to normal position, whereby the link 60 is moved downwardly to release the lever 53. The spring 49 thus is permitted to lift the clutch member 46 to bring the teeth 47 into meshing engagement 50 with the teeth 45 of the hub 44. The mechanism is now ready to begin another operating cycle.

The embodiment of the present invention illustrated in Figs. 5, 6, and 7 is quite similar to that above described, but differs therefrom somewhat in the operative connections between the shaft 18 and the screw shaft, and in some other structural details.

In said Figs. 5, 6, and 7 I have shown driving mechanism comprising a base 75 which is secured 75 to the frame 11 by bolts 76 or other equivalent

fastening means. Said base 75 is formed to provide a slideway in which is slidably mounted a plate 77. A screw shaft 78 is journaled in said base 75 and has threaded engagement with a hub 79 carried upon the plate 77, said screw shaft carrying a hand wheel 80 at its upper end. 5

Rotatably mounted upon the shaft 78 is an overrunning clutch which may take the form of a ratchet or any other desired one-way clutch construction. Since the details of this clutch 10 are not important to the present invention, I have illustrated simply an outer member 81 and an inner member 82, both of said members being rotatably mounted on the shaft 78, and said inner member 82 being formed with teeth for 15 cooperation with the teeth of a dental clutch member 83 splined on the shaft 78 and urged into engagement with the element 82 by a spring 84.

The outer element 81 of the one-way clutch 20 carries an arm 85 formed with a longitudinally extending slot 86, one end of a link 87 being adjustably secured in said slot 86. The opposite end of said link 87 is adjustably secured in the slot 89 of an arm 88 carried by a hub 90 secured 25 to the upper end of a shaft 91 suitably journaled in the base 75. At its lower end, the shaft 91 has secured thereto a second hub 94 having an arm 92 formed with a slot 93 in which is adjustably secured one end of a link 95, the opposite end of which is connected to an arm 96 mounted upon the shaft 18, said arm being provided with a plurality of apertures 97 whereby said link 95 may be adjustably connected thereto. 30

Pivoted at 98 at a point above the top of the base 75 is a lever, one arm 99 of which has pivotally connected thereto a rod 100 slidably associated with a hub 101 carried by the plate 77, said rod carrying an adjustable abutment 102 adjacent its lower end. 40

The opposite arm 103 of said lever is apertured to receive one end of a toggle link 104, the opposite end of which is secured to a finger 105 on a rocker journaled in a hub projecting upwardly from the base 75. Said rocker is provided with a handle 106 and with an arm 107 for cooperation with a pin 108 adjustably carried in a hub 109 mounted upon the plate 77. 45

The base 75 carries an arm or bracket 110 which supports a bearing for the outer end of 50 the main shaft 19 of the spinning frame. Said shaft 19 carries a pair of oppositely facing cone discs 113 and 114, the disc 114 being mounted upon said shaft for axial movement thereon and being urged toward the disc 113 by a spring 115 55 abutting said disc and a collar 116 mounted upon said shaft.

The plate 77 carries a motor 117 upon the spindle of which is mounted a V-pulley drivingly connected to the discs 113 and 114 by a V-belt 60 119.

The operation of this embodiment is very similar to that described hereinbefore. As the plate 77 is moved downwardly, the hub 101 engages 65 the abutment 102 to move the clutch member 83 out of engagement with the member 82. When the handle 106 is operated to elevate the lever arm 103, the lever arm 99 is held in position to hold the clutch member 83 out of engagement with the member 82. As the plate 77 is 70 moved upwardly by manual operation of the hand wheel 80, the pin 108 engages the arm 107 to release the lever arm 103, whereby the spring 84 is permitted to return the clutch member 83 to engagement with the clutch member 82. 75

The embodiment illustrated in Figs. 5, 6, and 7 has advantages over that illustrated in Figs. 1 to 4 in that removal and replacement of the belt 119 is facilitated, since the speed changing mechanism is removed from its substantial alignment with the shaft 19, whereby removal of the disc 114 from the shaft 19 is made practicable. Furthermore, the arrangement and configuration of the bracket 110 makes possible the use of the comparatively short shaft 19, and clears space which is occupied where the structures of Figs. 1 to 4 inclusive are used. When it is desired to move the belt 119 from the pulley 118, the bolts 76 may be removed, and the base 75 may be pivoted as a whole about its lower righthand corner, as viewed in Fig. 6, it being understood that the bearing block 111 is first disconnected from the bracket 110. Such movement of the base, of course, shifts the pulley 118 away from the spinning frame 10, and permits ready removal of the belt 119 from said pulley.

I claim as my invention:

1. In combination with a spinning frame including a bobbin spindle, a ring rail associated therewith, an oscillating shaft for reciprocating said ring rail, and a main shaft associated with said spindle and with said oscillating shaft to drive the same, means for driving said main shaft at variable speed, said means including a driving shaft parallel with said main shaft, an expandable pulley on one of said shafts and a pulley on the other of said shafts, means for shifting said driving shaft with respect to said main shaft in a direction transverse to the axis of said driving shaft, means operatively connecting said pulleys, and means including a one-way driving connection between said oscillating shaft and said shaft-shifting means.

2. In combination with a spinning frame including a bobbin spindle, a ring rail associated therewith, and a main shaft arranged to drive said spindle and ring rail, a prime mover, variable-speed transmission means connecting said prime mover to drive said main shaft, said transmission means including an element movable to vary the speed ratio between said prime mover and said main shaft, means driven by said main shaft and normally operable to shift said movable element, during operation of said main shaft, and automatic means for rendering said last-mentioned means ineffective to shift said movable element.

3. In combination with a spinning frame including a bobbin spindle, a ring rail associated therewith, and a main shaft arranged to drive said spindle and ring rail, a prime mover, variable-speed transmission means connecting said prime mover to drive said main shaft, said transmission means including an element movable to vary the speed ratio between said prime mover and said main shaft, means driven by said main shaft for shifting said movable element, clutch means interposed between said last-named means and said movable element, and means operable upon a predetermined degree of advancement of said movable element to disengage said clutch means.

4. The combination with a spinning frame having a main shaft, of means for driving said main shaft comprising, a base, a motor slidably mounted on said base and having a shaft parallel with said main shaft, pulleys carried by said shafts and connected by a driving belt, one of said pulleys being expandable, whereby movement of said motor on said base will vary the effective diam-

eter of said expandable pulley, means for moving said motor on said base, and means operatively connecting said main shaft to actuate said motor moving means.

5. Variable-speed driving mechanism comprising a base, a motor mounted on said base for sliding movement with respect thereto and having a shaft, a second shaft parallel with said motor shaft, pulleys carried by said shafts and connected by a driving belt, one of said pulleys being expandable, whereby movement of said motor with respect to said second shaft will vary the effective diameter of said expandable pulley, threaded means journaled in said base and cooperating with said motor to shift the latter on said base, and means connecting said second shaft to drive said threaded means.

6. Variable-speed driving mechanism comprising a base, a motor mounted on said base for sliding movement with respect thereto and having a shaft, a second shaft parallel with said motor shaft, pulleys carried by said shafts and connected by a driving belt, one of said pulleys being expandable, whereby movement of said motor with respect to said second shaft will vary the effective diameter of said expandable pulley, threaded means journaled in said base and cooperating with said motor to shift the latter on said base, an oscillating element driven by said second shaft, and means including a one-way clutch connecting said oscillating element to drive said threaded means.

7. Variable-speed driving mechanism comprising a base, a motor mounted on said base for sliding movement with respect thereto and having a shaft, a second shaft parallel with said motor shaft, pulleys carried by said shafts and connected by a driving belt, one of said pulleys being expandable, whereby movement of said motor with respect to said second shaft will vary the effective diameter of said expandable pulley, threaded means journaled in said base and cooperating with said motor to shift the latter on said base, an oscillating element driven by said second shaft, means including a one-way clutch and a two-way clutch connecting said oscillating element to drive said threaded means, and means operable, upon a predetermined extent of movement of said motor, to disengage said two-way clutch.

8. In combination, a base providing a slideway, a plate slidably mounted in said slideway, a threaded shaft journaled in said base and having its axis parallel to the axis of said slideway, said shaft threadedly engaging said plate, means including a two-way clutch for driving said shaft, and means associated with said plate and operable, upon movement of said plate beyond a predetermined position, to disengage said clutch.

9. In combination, a base providing a slideway, a plate slidably mounted in said slideway, a threaded shaft journaled in said base and having its axis parallel to the axis of said slideway, said shaft threadedly engaging said plate, a gear journaled on said shaft, driving means constantly meshed with said gear, a clutch element splined on said shaft and engageable with said gear to clutch the same to said shaft, and means associated with said plate and operable, upon movement of said plate beyond a predetermined position, to disengage said clutch element from said gear.

10. In combination, a base providing a slideway, a plate slidably mounted in said slideway, a threaded shaft journaled in said base and having its axis parallel to the axis of said slideway,

- said shaft threadedly engaging said plate, a gear journalled on said shaft, driving means constantly meshed with said gear, a clutch element splined on said shaft and engageable with said gear
- 5 to clutch the same to said shaft, resilient means urging said clutch element into clutching engagement with said gear, means associated with said plate and automatically operable, upon movement of said plate in one direction beyond a predetermined point, to disengage said clutch element from said shaft, resilient means manually actuated means operable to hold said clutch element against the tendency of said resilient means, and means associated with said plate and automatically operable, upon movement of said plate in the opposite direction beyond a predetermined point, to shift said manually actuated means to release said clutch element.
- 10 11. In combination, a base providing a slideway, a plate slidably mounted in said slideway, a threaded shaft journalled in said base and having its axis parallel to the axis of said slideway, said shaft threadedly engaging said plate, a gear journalled on said shaft, driving means constantly meshed with said gear, a clutch element splined on said shaft and engageable with said gear to clutch the same to said shaft, a spring urging said clutch element into clutching engagement with
- 15 said gear, a lever pivoted on said base, one arm of said lever engaging said clutch element, means associated with said plate and engageable with said lever arm, upon movement of said plate in one direction beyond a predetermined position, to disengage said clutch element from said gear, a rocker journalled in said base, a toggle link connecting the opposite arm of said lever with said rocker, and means associated with said plate and engageable with said rocker, upon movement of said plate in the other direction beyond a predetermined point, to release said lever and said clutch element.
- 20 12. The combination with a spinning frame having a main shaft, of a variable-speed driving attachment therefor comprising a base, a motor mounted on said base and having a shaft parallel with said main shaft, said motor being shiftable on said base in a direction transverse to the axis of its shaft, pulleys mounted on said shafts and connected by a driving belt, one of said pulleys being expansible, means connecting said main shaft to shift said motor, said belt and said last-named means constituting the only connection between said spinning frame and said attachment.
- 25 13. The combination with a spinning frame having a main shaft, of a variable-speed driving attachment therefor comprising a base providing a slideway and anchored on and secured to an element of said spinning frame, an arm secured to said base and providing a bearing for said main shaft, a motor mounted in said slideway and having a shaft parallel with said main shaft, pulleys mounted on said shafts and connected by a driving belt, one of said pulleys being expansible, and means connecting said main shaft to shift said motor.
- 30 14. In combination a base providing a slideway, a plate slidably mounted in said slideway, a threaded shaft journalled in said base and having its axis parallel to the axis of said slideway, said shaft threadedly engaging said plate; and means for driving said shaft, including a one-way clutch, both elements of said clutch being free to rotate on said shaft, means for driving one element of said one-way clutch, and a two-way clutch comprising the other element of said one-way clutch and an element splined on said shaft, all of said elements being positioned above said base, a lever pivoted at a point above said base and having one arm operatively associated with said splined element, resilient means urging said splined element toward clutching engagement with its complementary element, an apertured lug carried by said plate, and a rod connected to said lever arm and slidably received in the aperture of said lug, said rod having a stop thereon.
- 35 15. In combination a base providing a slideway, a plate slidably mounted in said slideway, a threaded shaft journalled in said base and having its axis parallel to the axis of said slideway, said shaft threadedly engaging said plate; and means for driving said shaft, including a one-way clutch, both elements of said clutch being free to rotate on said shaft, means for driving one element of said one-way clutch, and a two-way clutch comprising the other element of said one-way clutch and an element splined on said shaft, all of said elements being positioned above said base, a lever pivoted at a point above said base and having one arm operatively associated with said splined element, resilient means urging said splined element toward clutching engagement with its complementary element, an apertured lug carried by said plate, and a rod connected to said lever arm and slidably received in the aperture of said lug, said rod having a stop thereon.
- 40 16. In combination a base providing a slideway, a plate slidably mounted in said slideway, a threaded shaft journalled in said base and having its axis parallel to the axis of said slideway, said shaft threadedly engaging said plate; and means for driving said shaft, including a one-way clutch, both elements of said clutch being free to rotate on said shaft, means for driving one element of said one-way clutch, and a two-way clutch comprising the other element of said one-way clutch and an element splined on said shaft, all of said elements being positioned above said base, a lever pivoted at a point above said base and having one arm operatively associated with said splined element, resilient means urging said splined element toward clutching engagement with its complementary element, an apertured lug carried by said plate, and a rod connected to said lever arm and slidably received in the aperture of said lug, said rod having a stop thereon, a rocker mounted above said base, a toggle link connecting said rocker with the opposite arm of said lever, and an element carried by said plate and engageable with said rocker to release said lever from domination by said toggle link.
- 45 17. In combination, a base, a carriage slidable on said base, a motor mounted on said carriage and having a shaft, a driven shaft, pulleys on said shafts, one of said pulleys being expansible, and a belt providing a driving connection between said pulleys, an element movable to shift said carriage on said base, and means for controlling said element, comprising an oscillatory shaft, means connecting said driven shaft to oscillate said oscillatory shaft, one-way drive mechanism connecting said oscillatory shaft to move said element and means automatically operable upon movement of said element to a predetermined degree, to render said oscillatory shaft ineffective to drive said element.
- 50 18. In combination, a base, a carriage slidable on said base, a motor mounted on said carriage and having a shaft, a driven shaft, pulleys on said shafts, one of said pulleys being expansible, and a belt providing a driving connection between said pulleys, an element movable to shift said carriage

- on said base, and means for controlling said element, comprising an oscillatory shaft, means connecting said driven shaft to oscillate said oscillatory shaft, means including a clutch connecting said oscillatory shaft to move said element step by step in one direction, and means automatically operable, at a predetermined point in the cycle of operation of the organization to disengage said clutch, thereby rendering said oscillatory shaft ineffective to move said element.
- 10 19. In combination, a base, a carriage slidable on said base, a motor mounted on said carriage and having a shaft, a driven shaft, pulleys on said shafts, one of said pulleys being expandible, and

a belt providing a driving connection between said pulleys, an element movable to shift said carriage on said base, and means for controlling said element, comprising an oscillatory shaft, means connecting said driven shaft to oscillate said oscillatory shaft, means including a clutch connecting said oscillatory shaft to move said element step by step in one direction, and means carried by said carriage and automatically operable, upon movement of said carriage to a predetermined degree, to disengage said clutch, thereby rendering said oscillatory shaft ineffective to move said element.

PAUL B. REEVES.
